UNITED STATES PATENT OFFICE.

LEE M. HARLEY, OF PITTSBURGH, PENNSYLVANIA, ASSIGNOR TO JAMES H. MATTHEWS & COMPANY, OF PITTSBURGH, PENNSYLVANIA, A CORPORATION OF PENNSYLVANIA.

ROCKER DIE.

Application filed July 16, 1924. Serial No. 726,261.

To all whom it may concern:

Be it known that I, LEE M. HARLEY, residing at Pittsburgh, N. S., in the county of Allegheny and State of Pennsylvania, a citizen of the United States, has invented or discovered certain new and useful Improvements in Rocker Dies, of which improvements the following is a specification.

My invention relates to the construction of printing dies, specifically of dies which, shaped to a cylindrical surface, are used for printing brands on sheet steel, on packing-boxes, and for other such purposes. These dies are ordinarily formed of rubber, and the actual die body is formed as a rubber sheet removably secured to a rigid rocker body, to the end that one rocker body may be alternately equipped with a plurality of die bodies and so the instrument may serve for the printing of an indefinite variety of brands. Difficulties have attended the use of these rocker dies with removable rubber die bodies, difficulties due to stretching of the rubber under prolonged service, and to inequalities in the amount of stretching, with consequent difficulties in maintaining the die body properly centered on the rocker, and in getting a sharp imprint from edges and center alike. It is to the overcoming of difficulties of this nature that my invention is primarily addressed. Incidentally, and with further improvement in durability, I have modified the rocker-frame in the way of simplification and rigidity.

A rocker die embodying my invention is illustrated in the accompanying drawings. Fig. I is a view of the die in rear elevation, and Fig. II is a view in front elevation. Fig. III is a view in medial section, in the plane indicated at III—III, Fig. I. Fig. IV is a view to larger scale and showing in section a detail of the structure, on the plane indicated at IV—IV, Fig. II.

The rocker die is so far of familiar construction that it includes a frame having a rigid face 1, which in shape is a section of a cylinder, and handles 2 by which it is carried and applied. The die body consists of a sheet of rubber 3 (which I preferably form with an inlay of fabric), which sheet carries molded in relief upon it the die characters 4. It is the faces of these characters which constitute the printing faces of the

rocker die. In its application to the rocker frame the flexible die body is ordinarily backed, as is usual, by an interposed cushion layer 18. The layer 18 is ordinarily cemented to the face of the rocker.

It is in the anchorage of the sheet-like die body at its ends that the first feature of my invention is found. The cylindrical face 1 of the carrier is at its ends provided with rearward turned flanges 5. Against one of these terminal flanges—that shown at the right, Figs. I and III,—a clamping band 6 is removably secured. The particular construction is preferably characterized by these features; the clamping band 6 is formed of resilient material, preferably metal, and is inturned along one edge, and it presents to the flange a concave face. This band, near its ends, is removably secured to flange 5 by the wing-nuts 7 which engage bolts 8 extending from flange 5 and through the web of the band itself. The clamping pressure then comes immediately upon band 6 near its ends, and at midpoints in its width, where it stands away from the face of flange 5. This clearly appears in Fig. III. I remark here that the consequent bite of the clamping band upon the intruded end of the rubber die body 3 is secure, that the bite is adjustable, to take up slack, and that it is most secure toward the opposite side edges of the rubber die body. Fig. I shows the preferred arrangement, according to which the two clamping bolts 8 are spaced apart at an interval somewhat exceeding the width of the intruded end of the rubber die body, and Fig. II shows that the intruded end of the die body may be narrowed somewhat by tapering.

The flange 5 at the opposite end of the carrier—the left-hand end, Figs. I, II, and III—is provided at its ends with bearings 9, and in these bearings turns a rod 10 having a slot through it. At one end the slotted rod 10 may be adapted for manual rotation, as by flattening, indicated at 11. The rod 10 adjacent one end is provided with one or more notches, and the frame carries a tooth 12 which normally engages a notch in rod 10 and holds the rod against rotation in one direction at least. The tooth is adapted to yield under spring tension and recede from engagement with the

notch in the rod 10, and a push-button 13 is provided to effect such recession, but when the tooth is free it will enter a notch in rod 10, when in the rotation of the rod 5 the notch comes opposite. The notch-and-tooth engagement holds the rod 10 against rotation in die-releasing direction.

Operation is as follows. In applying a die body to the frame, one edge of the sheet 10 is first introduced beneath and secured by the clamping band 6. The opposite end of the sheet is then introduced through the slot in rod 10. The rod 10 is then rotated until the sheet is drawn taut upon the exterior of the cylindrical face 1 of the frame. As the rod 10 turns, the tooth 12 recedes (it may be in consequence of pressing upon push-button 13, or the notches may be formed as ratchet teeth, to allow such turning in tightening direction) but ultimately, 20 the tooth, engaging a notch, holds the rod against turning in opposite and die-releasing direction.

When a die body is to be removed from 25 the carrier, push-button 13 is pressed downward (Fig. IV) and so the tooth 12 is carried out of the ratchet groove in the rod 10. Rod 10 is then turned, and the die body released from engagement by it. The wing-nuts 30 7 at the opposite end of the frame are then loosened and the die body released from bar 6. Manifestly die bodies may thus be applied and interchanged at pleasure.

The anchorage is such that when a die 35 body has been applied, the securing means may be loosened and the die body may be grasped at either end and drawn in one direction or the other upon the face of the carrier, and may then be secured in the particular position to which it has thus been brought. In such manner the die body may be accurately placed on the carrier.

Such a die body in prolonged use stretches 40 somewhat. The rotating ratchet-held rod 10 at one end and the bolt-held clamping band 6 at the other, both afford take-up means for all consequent looseness. Furthermore, since such fullness may be taken up at either end or in part at each end, the 45 die may be maintained through prolonged service accurately centered on the carrier, and this is a feature of practical importance. In addition, it is to be remarked that when through prolonged service the stretching of 50 the die body has occurred and when, as is the case, this stretching is found to be greater along the opposite side edges than toward the mid-line of the die body, the anchoring means described are such as to take up that 55 irregular fullness and to maintain the die body always smooth upon its carrier.

I have spoken of the clamping band 6, and particularly of the intensification of the clamping force toward its ends and at the 60 edges of the intruded die body. This is a

feature of importance, since the strain of service tending to draw the die body from its anchorage is greater at the edges than at intermediate points.

It remains to speak of the structure of the 70 rocker frame and particularly of certain novel features which, simplifying and cheapening the structure and making it of lighter weight, strengthens it at the same time, to endure prolonged service. 75

The frame is made of sheet metal, preferably of aluminum, and is made of three plates. The cylindrical plate 1 with its back-turned flanges 5 has already been described. The other two plates are indicated 80 at 14 and 15. They in the assembled frame extend in parallel planes, perpendicular to the cylindrical surface of plate 1; their edges are shaped to the curve of the cylinder and they constitute backing for the plate 1, as 85 clearly appears in Figs. I and II. These plates 14 and 15 are provided at both ends with flanges 16, through which they are riveted to the flanges 5 of plate 1. Between plates 14 and 15 at opposite ends extend pins 90 17 on which the spool-like handles 2 of wood turn freely. These pins additionally are bracing and strengthening members for the frame.

It will be perceived that these plates 14 95 and 15 secured, as described, are truss members, to prevent any more violent curvature of plate 1, and that they are at the same time tension members, to prevent flattening 100 of the curve under the long-continued tension of die body 3 in service.

I claim as my invention:

1. In a printing die the combination of a rigid rocker frame with cylindrical face and a flexible sheet-like die body, the rocker frame 105 being provided at one end with a rearward extending flange, a clamping band of resilient material arranged opposite such flange and presenting to said flange a concave face, and means adjacent the ends of said clamping band for clamping said band to said flange, said rocker frame being further provided at its opposite end with means for drawing a clamped die body taut upon the 110 face of the rocker frame. 115

2. In a printing die the combination of a rigid rocker frame with cylindrical face and a flexible sheet-like die body, the rocker frame being provided at one end with a rearward extending flange, means cooperating 120 with such flange and adapted to clamp thereto one end of the die body applied upon it, with clamping strain most intense at the side edges of the die body, such means consisting of a clamping band of resilient material and adjustable anchorage for securing the clamping band to the said flange at either end, the two anchorages being spaced apart at a distance exceeding the width of 125 the die body, and means adapted to engage 130

the die body at its opposite end and to draw it taut upon the face of the rocker frame.

3. In a printing die the combination of a rocker frame including a cylindrical plate and two plates extending in planes perpendicular to the cylindrical surface of the first named plate and at their edges engaging the first-named plate from behind and at their ends secured to the first-named plate, and by such shape and arrangement serving as strengthening members of said first-named plate, and a die body facing said first-named plate and secured thereto under tension.

4. In a printing die the combination of a rocker frame including a cylindrical plate and two plates extending in planes perpendicular to the cylindrical surface of the first-

named plate and at their edges engaging the first-named plate from behind and at their ends secured to the first-named plate, and by such shape and arrangement serving as strengthening members of said first-named plate, bracing pins extending between the two plates last-named and adapted to serve as handles for the instrument, and a die body facing said first-named plate and secured thereto under tension. 20 25

In testimony whereof I have hereunto set my hand.

LEE M. HARLEY.
